FIRE EXTINGUISHER

Fred Albert Dodelin, Glen Ridge, N. J., assignor
to Pyrene Manufacturing Company, Newark,
N. J., a corporation of Delaware

Application July 26, 1938, Serial No. 221,280

4 Claims. (Cl. 169—31)

This invention relates to fire extinguishers, and is herein illustrated in connection with a fire extinguisher of the type wherein the fire extinguishing liquid is forcibly expelled under the action of a pressure-generating medium such as carbon dioxide normally contained within a sealed cartridge slidably supported within the extinguisher by a cartridge-retaining cage and adapted to be punctured, as it moves by gravity into operating position incident to inversion of the extinguisher, so as to render the contents of the cartridge available for use as a pressure-generating medium.

An important object of the present invention is to provide an improved extinguisher of the type mentioned and more particularly to provide a simple, reliable and inexpensive operating unit which comprises a cartridge cage, piercer, pressure-relief device and vent guard and which is adapted to be readily attached to the closure cap of a fire extinguisher so that such unit and such cap constitute a unitary assembly.

Other objects and advantages of the invention will become apparent from the following description when taken in connection with the accompanying drawing, in which—

Fig. 1 is a fragmental, central, vertical, sectional view of a fire extinguisher embodying the present invention, the above-identified operating unit being shown in elevation;

Fig. 2 is a view similar to that of Fig. 1 but taken at right angles and showing in section the pressure-relief device and vent guard which constitute parts of the operating unit;

Fig. 3 is a plan view of the extinguisher as viewed from above in Figs. 1 and 2, and

Fig. 4 is a horizontal, sectional view taken on line 4—4 of Fig. 2.

The fire extinguisher shown as embodying the present invention comprises a container 5, adapted for the reception of the fire extinguishing liquid to be forcibly expelled therefrom by way of a suitable hose and nozzle unit 6. The container 5 is equipped at its upper end with an externally screw-threaded collar 7, which affords a filling opening for the extinguisher. The collar 7 is adapted to receive a removable internally screw-threaded substantially flat closure cap 8, equipped with a gasket 10 adapted to engage the upper end of the collar 7 and thus form a liquid-tight seal when the closure cap is screwed down on the collar.

With the closure cap 8 there is associated an operating unit which comprises a cartridge cage, a piercer 14, a pressure-relief device 15 and a vent

guard 16, all constituting a unitary assembly which is readily attached to the closure cap 8 which is provided with a central hole for that purpose.

The cartridge cage includes a pair of substantially U-shaped frame members 17, between which is slidably held a conventional form of cartridge 18 normally containing a pressure-generating medium, such as carbon dioxide, and provided at its upper or head end with a closure 20 having therein a suitable seal, not shown, by which the pressure-generating medium is retained within the cartridge until such seal is punctured by the piercer 14 when the cartridge, incident to inverting the extinguisher, moves by gravity into operating position from the position in which it is shown. In order that the cartridge 18 may be so guided in its movement under the action of gravity as to insure proper axial alignment of the puncturable area of the cartridge seal with the piercer 14 at the instant the seal engages the piercer, the upper ends of the U-shaped frame members 17 are so shaped that they effectively cooperate with the upper or head end of the cartridge to positively guide and direct it with relation to the piercer, it being observed in this connection that the diametrical spacing of the leg portions of the U-shaped frame members 17 at their upper ends is such as to allow only a slight clearance between themselves and the upper or head end of the cartridge as it moves into cartridge-puncturing position.

The U-shaped frame members 17 are constructed from a suitable material, such as brass rods having more or less inherent resiliency, and normally tend to diverge so that when they are moved into a parallel relation, as shown in Fig. 2, their spring action may be utilized to effectively retain a cage-bottom-forming member in cartridge-supporting position, the cage-bottom-forming member being herein illustrated as a strap-like latch 21, one end 22 of which is looped about and thus hingedly connected to the base portion of one of the frame members and the other end of which is shaped to provide a hook 24 adapted to embrace the base portion of the other frame member. Additionally, the latch 21 is normally held in its position shown by reason of the fact that the cartridge 18 is of such diameter with relation to the diametrical spacing of the leg portions of the U-shaped frame members that, despite the substantial clearance which is afforded between the frame members and the cartridge, it is impossible, while the cartridge is positioned as shown in Figs. 1 and 2, to spring the frame-like

members sufficiently close together to permit the release of the latch. However, the clearance afforded between the frame members 17 and the cartridge 18 is ample, when the cartridge is 5 moved to a somewhat elevated position with relation to its position as shown in Figs. 1 and 2, to permit the frame members to be sprung close enough together to allow the latch to be released, thus permitting the latch to be moved upwardly 10 and then downwardly about its hinge connection. Upon releasing the latch 21, the cartridge 18 may be readily removed from the cage; and when inserting the cartridge the latch 21 may be closed, while maintaining the cartridge sufficiently elevated, by carrying out the converse of the latch-releasing operations just described.

The vent guard 16, with which the cage is permanently associated, includes a body member having upper and lower disc-like headers 25 and 26 which are spaced from each other and are connected together by a plurality of webs 27, within and to which are secured the upper ends of the frame members 17. The webs 27 are disposed slightly inwardly of the peripheral edges of 25 the headers 25 and 26, and near the outer margins of the headers are flange-like ledges 28 between which is confined an annular screen 30.

Attached to the center of the header 26 is the piercer 14, which may be of any approved form; 30 and the header 25 is provided with a tubular nipple 31, which is accommodated within an opening formed in the closure cap 8 where it is held by a retaining nut 32. Thus the vent guard 16, together with its associated cartridge cage, may be 35 attached to the closure cap 8 of the fire extinguisher. In order that a gas-tight union between the closure cap 8 and the top of the vent guard 16 may be afforded, a suitable gasket, not shown, may be introduced between the closure cap and the header 25. To the tubular nipple 31 is attached the pressure-relief device 15 which comprises a shell-like housing 34, the reduced or stem-like portion 35 of which is secured, by a screw-thread connection, within the nipple 31. 40 The housing 34 is formed with a ledge 36 on which is carried a suitable seal 37, the seal being of such a character that it will fracture under excessive pressure set up within the extinguisher. The seal 37 is maintained in gas-tight engagement 45 with the seat 36 by a tubular gland nut 38 carried within the internally screw-threaded portion of the housing 34. In order to protect the seal 37 against tampering and in order to preclude undue entrance of any foreign matter within the 50 central opening of the gland nut 38, there is provided a perforated disc-like shield 40 which is disposed above the gland nut and suitably held within the upper end of the housing 34.

From the foregoing description it will be understood that the operating unit—which includes the cartridge cage, the piercer 14, the pressure-relief device 15 and the vent guard 16—may be conveniently combined with a closure cap, such as that indicated by the numeral 8, so that such 60 unit and cap will constitute a unitary assembly for use with a fire extinguisher initially designed for operation under the action of a pressure-generating medium, such as carbon dioxide contained within and adapted to be released from a sealed cartridge. However, it will also be understood that in cases where it is desired to convert chemical reacting types of extinguishers, such as the so-called soda and acid types as well as the so-called foam types, into a cartridge type extinguisher, such conversion may be readily ef- 70

fected by substituting for the internal parts or units of such extinguishers the operating unit embodying the present invention. In such cases it becomes necessary merely to provide the closure cap with an opening adapted for the reception of the tubular nipple 31 so as to enable the operating unit to be attached to the closure cap in the manner herein described. 5

It is to be especially observed that regardless of whether the operating unit is used with a fire extinguisher initially designed for operation under the action of a pressure-generating medium or is employed in converting a chemical-reacting type of extinguisher into a cartridge-type extinguisher, the pressure relief device 15 assumes the 15 highly important function of relieving any excess pressure that may be built up within the extinguisher outside of the cartridge 18 and the vent guard 16 (particular reference being had to the annular screen 30 constituting an element of the 20 vent guard) insures against the passage of any foreign particles into the pressure-relief device by way of the inner end of its outlet passage, thus obviating any likelihood of the pressure-relief device becoming clogged and thereby failing to contribute that factor of safety which is required in extinguishers of the pressure-actuated type. 25

Although only one form of the invention is herein shown and described, it will be understood that various changes may be made without departing from the spirit of the invention or the 30 scope of the following claims.

What is claimed is:

1. For use in a fire extinguisher, a cartridge cage comprising a pair of substantially U-shaped 35 frame members spaced from each other and adapted to slidably receive therebetween a cartridge, and a cage-bottom-forming member hingedly carried by one of said frame members and adapted for interlocking connection with the 40 other of said frame members and serving as a support on which said cartridge normally rests.

2. For use in a fire extinguisher, a cartridge cage comprising a pair of substantially U-shaped 45 resiliant frame members spaced from each other and adapted to slidably receive therebetween a cartridge, means for supporting said frame members in a normally diverging relation, and a cage-bottom-forming member hingedly carried by one 50 of said frame members and adapted for interlocking connection with the other of said frame members and serving as a support on which said cartridge normally rests, the resiliency of said frame members being utilized upon establishing said interlocking connection to insure said cage-bottom-forming member against undue release. 55

3. For use in a fire extinguisher, a cartridge cage comprising a pair of substantially U-shaped frame members spaced from each other and adapted to slidably receive therebetween a cartridge, the leg portions of said frame members being shaped at their upper ends to present a restriction in the path of movement of said cartridge and thus maintain it against substantial deviation from a direct line of travel throughout at 60 least a portion of its sliding movement, and a cage-bottom-forming member hingedly carried by one of said frame members and adapted for interlocking connection with the other of said frame members and serving as a support on 65 which said cartridge normally rests.

4. For use in a fire extinguisher and adapted to be attached to a substantially flat closure cap provided at its center with a hole; an operating unit including a vent guard comprising an upper 70

header and a lower header and spacing elements maintaining said headers in a fixed and spaced relation to each other with a space between them and a tubular screen embracing said headers and 5 spacing elements, a tubular element communicating with the space between said headers and connected to and extending upwardly from said upper header and through the hole in said closure cap, means for securing said tubular element to 10 said cap with said upper header against the inside

of the cap, a pressure relief device connected to the outer end of said tubular element and adapted to relieve excessive pressure from within the extinguisher by way of said tubular screen and said tubular element, a cartridge cage attached to and extending downwardly from said vent guard, and a cartridge-piercer secured to and extending downwardly from said lower header.

FRED ALBERT DODELIN. 10
